RADIATOR

Charles Oppe and John J. Curello, New Haven, Conn., assignors to The G & O Manufacturing Company, New Haven, Conn., a corporation of Connecticut

Application February 25, 1933, Serial No. 658,572

4 Claims. (Cl. 257—130)

This invention relates to radiators and more particularly to engine-cooling radiators of the honeycomb type.

One of the objects of our invention is to provide an improved radiator core of the honeycomb type which is very efficient and relatively inexpensive, light in weight and yet strong.

Another object is to properly proportion the air passages relatively to the water passages.

Another object is to furnish a radiator core which is provided between the water passages with very effective means whereby heat can be carried from the water-containing walls into the air.

Another object is to provide effective means for dividing and utilizing the air entering the core at the forward face. It is aimed to avoid cool or cold cores of air traversing the core, and to cause all parts of the air entering the core to be brought into contact with metal walls of the core structure to effect transfer of heat.

To these and other ends the invention consists in the novel features and combinations of parts to be hereinafter described and claimed.

In the accompanying drawings:

Fig. 1 is a front elevation of a radiator core embodying our improvements, the same being broken away intermediate its top and bottom surfaces;

Fig. 2 is a side elevation of the core shown in Fig. 1 showing the core broken away between its front and rear surfaces;

Fig. 3 is a central vertical section of a portion of the core;

Fig. 4 is a section on line 4—4 of Fig. 2;

Fig. 5 is a section on line 5—5 of Fig. 2;

Fig. 6 is a detail elevation of a portion of one of the corrugated walls interposed between two adjacent water passages;

Fig. 6A is an enlarged detail section on line 6A—6A of Fig. 6;

Fig. 7 is a detail edge view of the upper portion of a unit of which a number are employed in manufacturing the core, the interposed air-deflecting walls being omitted;

Fig. 8 is a fragmentary edge view of the left-hand wall or plate adapted to be used in the unit;

Fig. 9 is a fragmentary edge view of the right-hand wall or plate;

Fig. 10 is a perspective view of a unit with parts broken away to show the interior structure;

Fig. 11 is a view similar to Fig. 1 but showing a modified construction;

Fig. 12 is a vertical central section through a portion of the core shown in Fig. 11;

Fig. 13 shows the interposed walls or plates used in the core shown in Figs. 11 and 12, these walls or plates in this instance being formed as a continuous strip;

Fig. 14 is a perspective view partly broken away

of a unit such as used to make up the core shown in Figs. 11 and 12; and

Fig. 15 is a detail face view of the right-hand air-deflecting wall shown in Fig. 13 looking from the inside.

In producing a radiator core embodying our invention we usually provide the core with generally upright zigzag water passages and with a plurality of generally horizontally disposed air passages passing through the core from front to rear, said core being made up of a plurality of generally loop-shaped sheet metal units which are assembled side by side, and when so assembled, create between them the intervening passages for the circulation of water. Usually the fluid to be cooled is water and the cooling fluid is air, and we mention this by way of example. Each unit usually extends from the bottom of the core completely to the top and comprises a corrugated sheet metal strip disposed generally in the form of a loop and having its ends suitably interconnected. When two such units are brought laterally into juxtaposition they form between them a sinuous or zigzag water passage. The corrugations in the strip extend transversely thereof and substantially horizontally, the opposite side edge portions of the strip being offset so that when the edges of one of the side walls are abutted against the edges of a side wall of the adjacent unit, a water passage of elongated cross-section and of suitable capacity will be created.

In Fig. 1 of the drawings we have shown an assemblage of three sheet metal units 20, 21 and 22, respectively, constituted in the manner above mentioned. These are all of identical structure, but it will be noted that the end joints 23, by means of which the ends of each strip are interconnected, are disposed in staggered relation in that where one unit has its joint 23 lowermost, for example, the next adjacent unit has such joint uppermost. In Figs. 3, 4, and 5 only two of the units are shown, and these views well illustrate the sinuous or zigzag water passage 24 formed by the juxtaposition of two units. The strip bent into loop form to constitute the outer walls of the unit is shown at 25, and the laterally offset edge portions of the strip are shown at 26. Between the offset portions the face of the strip is corrugated to form alternating ridges 27 and valleys 28.

In the form shown in Figs. 1 to 5, inclusive, there is interposed between the side walls of each unit a sheet metal heat absorbing inner structure consisting of two separate abutted corrugated plates, one of these plates being a so-called left-hand plate, as shown particularly at 29 in Fig. 8, and the other being a so-called right-hand plate, as shown particularly at 30 in Fig. 9. These plates when abutted face to face and inserted be-

5 between the lateral walls of the unit form in conjunction with the unit a cellular structure having three vertical rows of the approximately square mouths at the respective faces of the core, the mouths of the middle row being offset in a vertical direction from the mouths of the side rows, which latter are in horizontal alinement. One of the vertical rows of mouths of each unit is formed between a side wall of the unit and the plate 29. 10 The next vertical row is formed between the two plates 29 and 30, and the third row is formed between the plate 30 and the other side wall of the unit.

15 The interposed plates 29, 30 are corrugated transversely and preferably there is in the intermediate portion of each transverse corrugation a bend which serves to deflect the air and break up the air stream and cause all portions of the air entering the corrugation at one face to come into contact with the metal walls to abstract heat therefrom. In the particular form shown the corrugations have substantially V-shaped portions therein intermediate of their ends, the intermediate portions being constituted by V's which 20 are rather shallow. Preferably, as shown in Fig. 6, each valley extending across the strip has fairly long horizontal end portions 31 and an intermediate portion 32 in the form of a shallow V. Preferably the V-shaped portions extend through 25 approximately one third of the length of the air passage and each of the horizontal portions extends through approximately one third of the length of the air passage. Adjacent the junction of each horizontal portion with the V-shaped portion, the material of the sheet is struck up to 30 provide means for locating the strip relatively to its cooperating interposed strip and for preventing lateral displacement, this means being constituted by interfitting projections and recesses 35 on the strips or plates. In the particular form shown, each valley has associated with it toward one side edge of the strip a struck-up portion providing an inwardly directed locating projection 33 and toward the other side edge of the strip a struck-up portion presenting an inwardly fac- 40 ing recess 34, and then in the next valley there will be a depression 34 located toward the first-named edge of the strip and there will be a projection 33 located toward the other edge of the strip. In other words, the projections 33 and 45 recesses 34 will have a staggered relation on the strip. When the strips 29, 30 are placed face to face, each projection 33 engages the corresponding recess 34 in the other strip. As a consequence of the arrangement described there are 50 provided on the inner faces of each of the plates 29, 30 in regions spaced inwardly from the front and rear faces of the core bent-up or integrally formed centering or locating means situated at 55 the ridges projecting inwardly from the plates, the centering means in a given area located toward one face of the core consisting of alternating projections and depressions on the ridges arranged so that when one ridge has a projection 60 on its summit the next adjacent ridge will have a depression in its summit.

65 We also preferably provide suitable means for locating the plates 29, 30 relatively to the outer side walls of the units, and in the particular form 70 shown we have disclosed unit side walls having inwardly facing recesses 35 formed by indenting the strip, said recesses being at the summits or ridges of the corrugations. At points near the offset edge portions 26 of the units these recesses 75 85 serve to receive the ridge portions of the inter-

posed strips, these ridge portions fitting between slightly raised portions on the side walls of the unit in such a manner as to prevent the interposed strip from being dislocated relatively to the adjacent side wall.

90 It will be observed that the intermediate bends in the valleys of the interposed strips 29, 30 register with each other, or, in other words, the opposed intermediate V-shaped portions of the two strips are in horizontal alinement, and, therefore, 10 there are created between the two strips a number of passages extending from front to rear of the core and having bends therein by which the air is deflected out of its course and then back into its course in passing from the front of the 15 core to the rear. On the other hand, there are formed between each interposed strip and the adjacent side wall of the unit a plurality of generally square mouths at the front and rear of the core, and each of these mouths communicates 20 with a passage portion at the middle part of the core which is substantially straight at one side but on the other side has a return bend therein. As a result of having the V-shaped bends extend for approximately one third the length of 25 the air passages and the horizontal portions each extending approximately one third the length of the air passage, the area of air turbulence in the passage is so located as to place it where it is most needed, and on the other hand the horizontal 30 portions of the air passages provide continuous solder-contacting areas leading from the water passage walls, which areas are relatively large and of great effectiveness for carrying heat away from the water passage walls.

35 In the structure above described it will be understood that where the V-shaped bends in the air passages formed between the interposed strips have the apices of the V's lowermost, the apices of the V's in corresponding air passages of the 40 next adjacent units will be uppermost. This is shown in Figs. 1 and 3 of the drawings.

45 In the form shown in Figs. 11 to 15, inclusive, we make up the enclosing wall of each cellular unit in the manner previously described, but instead of interposing two separate strips between the lateral walls, we interpose interconnected strips forming parts of a continuous member bent intermediate of its ends and returned upon itself in the manner shown particularly in Fig. 13. 50 The continuous member or strip is transversely corrugated as before, and has return bends in the valleys of its corrugations, and may, in fact, be stamped up so as to have the same configuration as the strips 29 and 30 previously described, 55 although of about twice their length.

55 In Fig. 11 we have shown three units 20^a, 21^a, and 22^a, corresponding in arrangement to the units 20, 21, and 22 previously described. The 60 interposed doubled strip is shown at 36, and the folded portion of this strip which integrally connects the side walls of the interposed structure is shown at 37. One of the principal differences over the form shown in Figs. 1 to 10, inclusive, consists in the fact that due to the 65 doubling of the interposed strip the air-deflecting passages at the inner face of the one side wall thereof are oppositely disposed with reference to those at the inner face of the opposite side wall, as shown particularly in Figs. 14 and 15. In 70 other words, where the air-deflecting channels are of V-shape, as shown, the apices of the V's in one side portion of the strip are uppermost and apices of the V's in the opposite side portion of the strip are lowermost. In Fig. 15 some of 75

the V's of the left-hand strip portion are shown in dotted lines. The result of this arrangement is that the air passages located between the interposed walls are of quite irregular form in a zone intermediate of their ends. At their ends they are of substantially square or rhomboidal shape, but intermediate of their ends they have at one side a channel deflected in one direction and at the opposite side a channel deflected in the opposite direction. Air passing through such a passageway is given great turbulence and the stream of air is very effectively broken up with complete elimination of any cold core of air and with consequent effectiveness of heat transfer.

In the form last described, it is preferred to alternate the interconnected ends 37 of the doubled strips so that where in a given unit the interconnected end 37 is uppermost, the interconnected end of the strips of the next adjacent unit will be lowermost. This is clearly shown in Fig. 11.

The operations of soldering together the different parts of the core assemblage are carried out in the usual manner, and need not, therefore, be described in detail. It will be understood, however, that the solder in which the core is dipped at its opposite faces effectively secures the interposed strips to each other and to the side walls of the loop-shaped units into which they are inserted.

By our invention a light-weight but very strong radiator can be provided and one in which the area of the air passages has such a relation to the area of the water passages as to promote the highest efficiency. The air encountered by the front face of the core is so divided and utilized as to have a very superior cooling effect, and in particular the air passages formed between the side walls of the radiating structures set in between the walls of the water passages are of great advantage in extracting from such radiating structures heat which has been carried by conduction into those structures from the water passage walls.

While we have shown some preferred embodiments of our invention, it is to be understood that we have not attempted to illustrate or describe the various modifications which may be made without departing from the principles of our invention. Various changes may be made in the detailed structure without going outside of the limits defined in the claims.

What we claim is:

5. 1. In a radiator, a core having a plurality of transversely corrugated sheet metal walls forming a plurality of generally upright water passages spaced laterally from each other, and transversely corrugated sheet metal strips set in face to face between each water passage and the adjacent water passage, said strips having V-shaped corrugations therein creating passages to carry air from one face of the core to the other face, said air passages having horizontal front and rear portions aggregating about two thirds of the total air passage length and a V-shaped intermediate portion of a length corresponding approximately to one third of the length of the air passage, said strips having soldered contact with the water passage walls substantially throughout the length of the horizontal portions of the air passages.

2. In a radiator, a core having a plurality of transversely corrugated sheet metal walls form-

ing a plurality of generally upright water passages spaced from each other laterally, transversely corrugated sheet metal strips set in between each water passage and the adjacent water passage, said strips forming between them passages for carrying air from the front face of the core to the rear face thereof, said air passages each having a horizontal front end portion and a horizontal rear end portion and a shallow intermediate V-shaped bend for creating air turbulence in the air passage, each horizontal end portion taking up approximately one third the air passage length and said V-shaped bend the remaining third, and means located on the ridges of the corrugations which will extend toward each other at the inner faces of said strips for locating one strip relatively to the other and preventing relative displacement of the strips, said means comprising bent-up portions located on said ridges adjacent the junction of the horizontal passage portions with the V-shaped portions, said bent-up portions being in the form of projections on certain ridges alternating with depressions in the adjacent ridges, each projection extending into the opposite depression of the other strip.

3. In a radiator, a core having a plurality of transversely corrugated sheet metal walls forming a plurality of generally upright water passages spaced from each other laterally, and transversely corrugated sheet metal members set in between each water passage and the adjacent water passage, said members forming between them air passages leading from the front face of the core to the rear face thereof and having square mouths and horizontal portions located adjacent the front and rear faces respectively of the core and V-shaped bends intermediate the horizontal portions for creating turbulence in the air passages, said members being formed as parts of an integral strip and the V-shaped bends of opposing members extending in opposite directions, said V-shaped bends extending through approximately one third the length of the air passages and the horizontal portions of the air passages each extending through approximately one third the length of the passages.

4. In a radiator, a core having a plurality of transversely corrugated sheet metal walls forming a plurality of generally upright water passages spaced from each other laterally, and transversely corrugated sheet metal members set in between each water passage and the adjacent water passage, said members forming between them air passages leading from the front face of the core to the rear face thereof and having square mouths and horizontal portions located adjacent the front and rear faces respectively of the core and V-shaped bends intermediate the horizontal portions for creating turbulence in the air passages, said members being formed as parts of an integral strip and the V-shaped bends of opposing members extending in opposite directions, and means on the ridges of the corrugated members which extend toward each other at the inner faces of the members for centering the members relatively to each other, said members having solder-contact with the water passage walls substantially throughout the length of the horizontal portions of the air passages, said horizontal portions each being substantially one third the length of the entire air passage.
